UNITED STATES PATENT OFFICE.

ALEXANDER G. E. WESTMACOTT AND JAMES PEMBERTON HUTCHINSON, OF NEWTOWN, PENNSYLVANIA.

RAILWAY.

SPECIFICATION forming part of Letters Patent No. 468,608, dated February 9, 1892.

Application filed April 7, 1891. Serial No. 388,009. (No model.)

To all whom it may concern:

Be it known that we, ALEXANDER G. E. WESTMACOTT, a subject of the Queen of Great Britain, and JAMES PEMBERTON HUTCHINSON,

5 a citizen of the United States, both residing at Newtown, Bucks county, Pennsylvania, have invented certain new and useful Improvements in Railways, of which the following is a full, clear, and exact description, reference 10 being had to the accompanying drawings, forming a part of this specification.

Our invention relates to street-railways; and it consists of a treading-surface and longitudinal stringer of specific conformation combined 15 in one piece of metal, in the combination therewith of a metallic cradle conforming to the curvatures of the stringer as a supporting device and as a joint-piece, and in the minor details of the construction, all as hereinafter 20 more particularly set forth, the object of our invention being to supply a rail especially adapted to street-tramways, and in which the same may be laid, if desired, without the use of the usual cross-tie.

25 In the drawings illustrating our invention, Figure 1 is a plan view of our improved railway, showing two of the rails and their combined stringers supported in the cradles at the joints thereof and the gage of the tramway 30 secured and regulated by the tie-rods. Fig. 2 is a side elevation thereof at joint, showing cradle. Fig. 3 is a cross-section through the line *a b* of Fig. 2.

In the construction of street-tramways the 35 top surface of the rail is usually of the form shown in the upper part of Fig. 3, above the line *c d*, which requires that the rail should be supported upon and secured to longitudinal stringers, which in turn are fastened to 40 cross-ties embedded deeply in the soil, with the usual paving as a superstructure. The chief objections to this mode of constructing street-trams are the destruction of the cross-ties and stringers from the action of air and moisture 45 and the large expense of removing and relaying the paving necessary both in the original construction and in the repairs. Our invention simplifies the construction of the roadway and greatly improves the durability thereof.

50 The rail proper above the line *c d* and

marked A, Fig. 3, is constructed, as shown in said figure, integral with the stringer, which is composed of two sides *B B'* of double curvatures, essentially as shown in cross-section, Fig. 3, until they meet at the base in a vertical plane passing longitudinally through or near the center of the top surface of the rail. This particular form of the stringer portion of the rail, embedded in the ballast between the cradles or chairs *C*, hereinafter mentioned, 55 operates to prevent a rolling or turning or displacement of the rail from a true horizontal position, when, as frequently happens with street-railways, heavy wagons pass over the tracks unevenly, bearing sometimes upon the 60 tread and sometimes upon the flange of the rail, tending thereby to change its horizontal alignment. The double curvature of the stringer also imparts great elasticity to the 65 integral structure. These combined rails and 70 stringers are supported at their joints in chairs or cradles *C*, which are shaped internally to conform to the double curves of the stringer portion of the rail and stringer combination, the said parts being secured together by tie-rods *E E*, which pass laterally through the 75 two sides, respectively, of the chair or cradle and stringer, and these rods, being made of sufficient length, can be made to serve the purpose of tie-rods between the two parallel 80 rails, as shown in Fig. 1, each end of said rod uniting the said parts *B* and *C* together, as described. Additional tie-rods *F* (see Fig. 1) are preferably supplied to secure the proper 85 gage of the tramway, and they are applied to the stringers *B B'* about equidistant between the two ends of the rail, and therefore between each set of cradles or chairs *C*.

The tie-rods *F* may be constructed similarly 90 to the tie-rods *E E*, which consist of the rod *E*, the screw-threaded ends *h*, and threaded nuts applied thereto on each side of the chair or cradle *C*. By means of these appliances and of slots and keys in the rods between the two tracks it will be apparent that the gage 95 of the railway may be readily adjusted and maintained. We prefer to use in addition thereto separate means for adjustably fastening the chair or cradle to the stringers of the rails at their joints, consisting of a screw- 100

bolt L, with threaded nuts on each side thereof, as shown in Fig. 1.

In laying our improved railway the chairs or cradles C rest in ballast only, and no 5 sleeper or tie is necessary. In order, however, to secure more perfect and continued alignment, we prefer to rest the cradles or chairs C on blocks of metal or stone D, conforming to the external shape of the said cradle C, 10 (see Fig. 3;) or the chair C may be given an external shape similar to and in lieu of separate blocks D.

We desire it to be understood that we do not confine our invention to a combined rail 15 and stringer in which the upper surface or tread of the rail proper is of the specific conformation shown in the drawings, as the latter may be varied and any well-known form of street-rail tread adopted in place of that 20 shown, the essence of this part of our invention being the combination of such a rail with a stringer, consisting of inwardly-inclined concavo-convex sides made integral therewith and meeting at the base.

25 Having thus described our invention, what we claim as new, and desire to secure by Letters Patent, is—

1. A combined street-railway rail and stringer consisting of the rail proper or tread A, with longitudinal sides B B', formed 30 integral therewith and of concavo-convex

form, inclining inwardly toward each other and meeting at the base, substantially as described.

2. A combined street-railway rail and 35 stringer consisting of the rail proper or tread A, with longitudinal sides B B', formed integral therewith and of concavo-convex form, inclining inwardly toward each other and meeting at the base, in combination with 40 a chair or cradle C, conforming on its interior to the external shape of the stringer, substantially as described.

3. A combined railway rail and stringer 45 consisting of the rail proper with longitudinal sides formed integral therewith and inclined inwardly toward each other and meeting at the base, in combination with a chair or cradle conforming on its interior to the external shape of the stringer, and with tie-rods 50 E E passing through the same and connecting the two sets of rail stringers and chairs forming the tramway, substantially as described.

In testimony whereof we have hereunto 55 affixed our signatures this 28th day of March, A. D. 1891.

ALEXANDER G. E. WESTMACOTT.
JAMES PEMBERTON HUTCHINSON.
